DAVID ROBERT YARNALL, OF PHILADELPHIA, PENNSYLVANIA, ASSIGNOR TO
YARNALL-WARING COMPANY, OF PHILADELPHIA, PENNSYLVANIA, A CORPO-
RATION OF PENNSYLVANIA.

CONSTANT-SPEED INTEGRATOR.

1,186,639.

Specification of Letters Patent. Patented June 13, 1916.

Application filed August 17, 1912. Serial No. 715,549.

To all whom it may concern:

Be it known that I, DAVID ROBERT YARNALL, a citizen of the United States, residing at 316 Preston street, Philadelphia, in the county of Philadelphia and State of Pennsylvania, have invented a certain new and useful Constant-Speed Integrator, of which the following is a specification.

The purpose of my invention is to accommodate a mutilated surface integrator to uses where a high degree of accuracy is required.

A further purpose of my invention is to rotate the mutilated surface at such a speed that no fluctuation of rate of flow shall take place between engagements with the mutilated surface, which fluctuation is large enough to interfere with attaining the required or designed degree of accuracy.

20 A further purpose of my invention is to catch small cycles of movement of the member determining the registration of an intermittently actuating integrator.

I prefer to illustrate my invention by one compact, efficient, inexpensive and wholly satisfactory form thereof only, while recognizing that my invention might be used to advantage in a variety of other physical embodiments.

30 Figure 1 is an elevation of the preferred form of my invention, the electric circuits being shown in part diagrammatically. Fig. 2 is a diagrammatic illustration of the motor-actuating circuit. Fig. 3 is a rate of flow curve.

This application contains divisional matter from my application for constant speed electrically operated integrator, filed August 9, 1911, Serial No. 643,191.

40 In order that the relation of the various parts in my invention may be clearly understood I have illustrated sufficiently for a clear understanding even where the parts have not involved my invention. Thus the 45 forms of recorder and integrator shown are not my invention *per se* nor are the specific form of electric motor and governor thereof. These, however, are illustrated as fully as shown because of the combination formed 50 and their excellence in carrying out my invention.

I have illustrated a weir float 1 actuating a rack 2, through suitable guides, with indi-

cation of the movement by pointer 3 upon dial 4, and rotation of the indicating drum 55 5 through pinion 6 and shaft 7. The actuating drum curve 8 is calibrated in agreement with the notch or orifice used. This may bear the five halves (5/2) power or three halves (3/2) power relation to the 60 height of the water above the notch, corresponding to the V or rectangular notch respectively, or other notch or submerged orifice, in any theoretical or empirical relation desired. The walls of the drum curve, engage and drive a finger upon arm 9 fixed upon longitudinally movable shaft 10, which carries also the recording pen support 11. This is moved over the card 12 upon recording cylinder 13 in agreement with the rate of 70 flow, and the rate of revolution of this drum, by means, usually clockwork, not shown, is in proportion to the time of flow.

The shaft 10 carries a well known type of counter 14 which is actuated by means of 75 gear 15. The gear is fixed, longitudinally of the counter, and the counter moves bodily along the surface of drum 16 to engage with mutilated teeth or surface 17. The gear teeth or elements of the surface in the cylinder form are parallel to the axis. In the disk form they are radial and range between these two limits in various conical forms used. These elements are so proportioned as to provide for engagement of a number of 85 teeth or a circumferential extent of surface, in any position of the gear 15, in proportion to the flow, here of water over the notch or through the orifice, at that position. The cone supports for the several parts are adjustable in brackets 19.

The main integrator in present use is of the mutilated gear or surface type. Consequently, I have stated the objectionable character of its present drive and have shown 90 the advantages of my invention in connection with this integrator. Both would be true, however, of any other form of variable intermittently-actuating integrator and I do not wish to confine my invention to the 1 present type only.

I prefer to use an electric motor for moving the mutilated surface, rather than the clockwork previously in general use, because the electric motor conveniently gives a 10 higher speed, is much more positive, hav-

ing a larger balance wheel effect, is less bulky, avoids accidental time lapse from failure to wind and needs no leveling. A relatively high speed is desirable, in order to secure one or more rotations of the mutilated surface within each cycle of sufficient volumetric magnitude to require representation within the degree of accuracy required. The fluctuation of the flow, if not effective to vary the integrator reading, is lost and the measurement is inaccurate, whether the fluctuation take place while the integrator counter is in engagement with the mutilated surface or during a gap between engagements of the counter with the surface. Where double fluctuations of the rate of flow completing a cycle take place during continued engagement or disengagement of the counter wheel with the mutilated surface of the integrator, the variation in quantity represented by the cycle, is entirely lost, since the integrator has not caught any part of it.

It will be apparent that the counter gear does not register at all during the entire free operation of the gear and that, particularly for light loads, the most of the rotation is without registration. The sensitivity of the instrument to fluctuations is therefore dependent primarily upon the speed and this is more pronounced the lighter the load.

I combine a motive power having sufficient balance wheel effect to be unaffected by the differences in friction when engaged and disengaged, with a speed which catches the lesser, as well as the greater fluctuations and gives correspondingly increased accuracy, with greater reliability.

I have illustrated the motor conventionally at 20, without any detail, as the exact form of motor is not material. It is preferably mounted upon the same frame as the rest of my mechanism herein illustrated.

The armature shaft is extended at 21, and a contact cylinder 22, is formed upon it. It also carries a frame 23, having standards 24 and 25, upon the latter of which is provided an arm 26, whose bell-crank extension 27, is threaded to carry a major adjustable weight 28 and a minor adjustable weight 29, both of which are effective, centrifugally, to bring tension upon the spring 30. This varies the position of the arm 26, and the distance of a contact 31, from an adjustable co-operating contact 32, shown as screwed into bracket 33, by means of head 34. It is locked in its position by a nut 35. The arm 26 is adjusted to a predetermined position or afterward calibrated to bring a pointer or mark 36 upon it in line with the mark 37 upon standard 24 when the intended speed has been attained. The making and breaking of electrical connection through the contacts 31 and 32 is effective, through means

hereinafter described, to maintain the speed of rotation. The current is brought to contact point 31 through a circuit including the governor frame, the arm 26, the contact cylinder 22, brush 38, and support 39, from one end of resistance 55 of the motor circuit while the other end of resistance 55 is connected to support 33. The governor thus forms an intermittent shunt, or more properly, short circuit for the resistance 55.

I provide a shaft 40, suitably supported in bearings 41, and mount upon it a worm gear 42, to engage with a worm 43, upon shaft 21. A sprocket wheel 44, upon this shaft 40, is connected with and rotates a sprocket chain 46. The cylinder 16 is thus rotated. It is obvious that other means of transmitting rotation may be employed. The worm gear and sprocket gears are so proportioned in view of the predetermined motor speed as to give the requisite speed of rotation to the integrator cylinder 16.

The registering marks 36 and 37 afford a visual means of checking the position of the lever 26, but this does not check the accuracy of the adjustment thereon intended to be indicated and I have therefore provided a check for the speed of the motor, which is simple and accurate, inexpensive and capable of being used by the most ignorant workman.

I extend the shaft 40, supporting it as desired in bearing 47, and place the bevel gear 48 upon it to mesh with a suitably supporting bevel gear 49 causing rotation of a pointer 50, about a dial 51. The gears 49 and 48, are here representative of any gearing required to cause desired revolution of pointer 50, just as the two sprocket wheels 105 and chain shown indicate the connections of these parts by suitably proportioned connecting gear. I select this speed of rotation and the marking upon the dial 51 so that with the given speed of the motor the 110 pointer 50 shall move in agreement with time intervals marked on the dial, such as five minutes, quarter hour or hours and the passage of the pointer between these time graduations may be checked at any time, 115 quickly, without computation, and without the resetting of the speedometer. It involves time comparison only.

In the diagrammatic representation of Fig. 2, I have shown two field windings 120 52 and 53, in series with the armature winding 54. This is the preferred arrangement of the motor winding. Part of the time the resistance 55, is in series with the armature and field windings and the rest of the time 125 it is short circuited by the contacts 31 and 32. Whether the resistance 55 is in series with the field and armature coils, or is short circuited, I have preferred to use the resistance 56 in series with these coils. The 130

electromotive force is applied to the circuit from any suitable source shown diagrammatically at 57. Where the speed desired for the rotation of the integrator element is such that the inertia of the gear 15 threatens to continue its rotation after this wheel has left the part of the mutilated surface by which it is turned, this inertia may be checked by any suitable retarding means, of which one form is shown in brake 58.

In Fig. 3 I have illustrated a rate-of-flow curve 59—60 in which the distances along the line B—A represent quantities of flow and the distances along the line B—C represent time. I have not considered it necessary to indicate exact time relation to flow as this will vary widely in different installations. Applying the invention to the measurement of water: I prefer to use my invention in connection with a weir or submerged-opening meter in which the rate of flow into the chamber above the weir, or opening, is limited. Most desirably I use it in connection with meter mechanism of the type shown in my Patent No. 1,159,148, issued November 2, 1915, for combined feed water heater and weir meter, in which the rate of flow of the water into the chamber above the weir is limited by the size of the inlet to this chamber. This sets a limit to the rate at which the flow over the weir can increase as not greater than that represented by the angle of the line 61—62 with the horizontal. The greatest rate of reduction of flow will take place when the flow is at a maximum and the valve controlling admission of fluid is suddenly closed. I have represented the limiting angle of rate of reduction of flow by the line 63—64. Obviously, the first of these angles may be varied in the design of the plant by variation of the inlet, or of the shape of the weir or opening and the second may be varied by the latter method. In any event, if the distance between the points 65 and 66 on the curve represent the time during which the wheel or gear 15 is uninterruptedly connected with the operating part of the mutilated surface, or uninterruptedly disconnected therefrom the variation of the curve between, from the straight line 65, 66, indicates that there has been an additional quantity of flow which has not been measured at all and, correspondingly, an error in measurement.

I purpose rotating the mutilated element rapidly enough for any given permissible maximum rates of change of flow so that the volume represented by any such peak or corresponding valley (if the variation takes place at the bottom of a cycle) which is not "caught" shall not appreciably affect the accuracy of the integration as compared with the permissible error, within a reasonable time of test duration. I have succeeded in reaching a degree of accuracy of 99% in

measurements ranging over an hour or more with great reliability in the case of boiler feed measurement and with six rotations of the mutilated element per minute and consider this rate ample for such duty. 70 I find that at the speed named six rotations per minute also provides several rotations of the mutilated element for each cycle of any fluctuation of sufficient magnitude for its omission in registration to appreciably affect the accuracy of measurement. Where the rate proposed causes rotation of any of the intermittently operated parts fast enough for their inertia to interfere with accurate operation, I prefer to 80 drag said part or parts, as already suggested. Here again the advantage of a motor having considerable balance wheel or inertia effect, becomes noticeable in the attainment of the speeds required; as the drag which with this motor is negligible, would interfere with the accuracy of, or unduly tax other forms of motor. It will be evident that I provide for increased frequency of 85 actuation of a recording element whose record is dependent upon the condition or rate of the flow which is to be measured.

I find that it is quite desirable to actuate integrator elements, here the mutilated cylinder, with sufficient rapidity so that the variation between release and reengagement or engagement and release of the integrator wheel or gear with the mutilated surface may be too short for fluctuation during either interval to appreciably affect the integration within the degree of accuracy contemplated, most desirably rotating the mutilated surface several times within a period of time appreciable from the standpoint of the degree of accuracy intended. For use 100 upon feed water for boilers, my experiments have led me to believe that the most desirable frequency of rotation is approximately six a minute, though it would be evident that different speeds of rotation may be desired by different designers and for different uses in carrying out the principles of my invention. It will also be evident that while a lower speed of rotation would result in reduced protection against inaccuracy of 110 registration, a greater speed of rotation would increase the accuracy coefficient.

Having thus described my invention, what I claim as new and desire to secure by Letters Patent is:

1. In an integrating mechanism, a rotatable member having a mutilated surface, a wheel displaceable in the direction of the axis of rotation of said member and in engaging relation therewith, and a driving 125 means for said mutilated member, said surface being rotated one or more times during the period elapsing between the beginning of the displacement of said wheel and the end of said displacement. 130

2. In an integrating device, a rotatable member having a mutilated surface, a wheel in engaging relation therewith and displaceable parallel to a surface element of said member and means to rotate said member one or more times during the time elapsing between the beginning and the end of the movement of said displaceable wheel.
3. In a device of the character stated, a mutilated surface integrator including a register - actuating wheel, current - actuated means for moving said wheel along the mutilated surface a distance proportional to the current flow, and a constant speed motor for rotating the surface one or more times during each cycle of change of flow which cycle varies the rate undesirably as compared with the percentage of error permitted.
4. In an integrating mechanism, a rotatable member having a mutilated surface, the circumferential extent of engaging parts of which varies directly with the distance along the length of an element of the surface, a wheel displaceable in the direction of an adjoining element of said member and in engaging relation therewith, a fluid-actuated member movable at a different rate from the rate of flow of said fluid, connections between the fluid-actuated member and the wheel correcting the rate of movement of the wheel to correspond with the volume of flow of the fluid and driving means for said mutilated member, driving said surface into engagement with the wheel one or more times during the period elapsing between the beginning of displacement of said wheel for any variation in current flow and the end of said displacement.
5. In an integrating mechanism, a rotatable member having a mutilated surface the circumferential extent of engaging parts of which varies directly as the distance measured along an element of the surface, a wheel movable in the direction of an element of said surface and in engaging relation therewith, a liquid-actuated float movable at a rate different from the rate of volume of flow of the liquid, connections between the float and the wheel correcting the variation of rate of movement of the float and liquid to move the wheel proportionately to the volume of liquid flow and driving means for said mutilated member adapted to move the engaging surface of the mutilated member into contact with the wheel one or more times during the period elapsing between the beginning of any displacement of said wheel and the end of said displacement.

DAVID ROBERT YARNALL.
